PRIMING DEVICE FOR PUMPS

Adrian P. Adney and Benjamin D. Barton, Battle Creek, Mich., assignors to American-Marsh Pumps, Inc., Battle Creek, Mich.

Application April 7, 1941, Serial No. 387,204

6 Claims. (Cl. 137—68)

This invention relates to improvements in priming device for a pump.

The main objects of my invention are:

First, to provide an improved primer for engine driven and engine primed pumps in which the possibility of damaging the engine in consequence of its priming function is eliminated.

Second, to provide a priming device of the foregoing character which is extremely quick and effective in its action of evacuating air from an engine driven pump casing.

Third, to provide a device of the type described which is simple in its parts and not likely to become jammed, but which has provision for nullifying the damaging effect of jamming should it occur.

Further objects relating to details and economies of my invention will appear from the description to follow. The invention is defined in the claims.

A structure embodying the features of my invention is illustrated in the accompanying drawing, wherein:

Fig. 1 is a fragmentary view somewhat diagrammatically illustrating the priming structure of the present invention in an arbitrary relation to a pump and an engine employed in operating the priming device and pump.

Fig. 2 is a fragmentary view in vertical section illustrating structural details and relationships in the priming device of my invention.

Generally considered the present invention relates to priming devices for centrifugal engine driven pumps, and more particularly to pumps of this character in which the priming device is operated from the intake manifold of the pump actuating engine. In hitherto known priming devices of this type, notwithstanding the fact that priming cut-off provisions have been utilized to terminate the operation when the pump reaches a primed condition, cases have occurred in which the engine cylinder head was damaged due to induction of water or liquid into the intake manifold following the priming of the pump. Such is usually due to jamming of the parts. The present structure has relatively simple yet highly effective means incorporated therein for eliminating any likelihood of such damage in a positive and unfailing manner.

Referring to the drawing the reference numeral 1 is employed to indicate a portion of the casing or volute of a rotary centrifugal pump to which the priming device 2 of the present invention is suitably connected by fittings 3 and 55

interposed flexible hose 4, this connection preferably being on the intake side of the pump.

The reference numeral 5 designates an internal combustion engine of conventional type to which the intake manifold 6 of which the priming device 2 is connected by means of an air line 7.

The priming device 2 consists of a hollow primer body or casing 8 which is adapted to be secured as by bolts 9 to a suitable supporting surface, preferably beneath the hood of the actuating engine 5. In practice the attachment is preferably made to the engine cylinder block, to the end that the heat of the engine shall prevent freezing of water in the primer when operated in cold weather.

The casing 8 provides a lower relatively large intake and float chamber 10 into the lower side of which the liquid intake fitting 3 is tapped and in this chamber a float 11 is pivotally mounted at 12 on an arm 13. The casing 8 has an opening 14 on the top thereof which is closed by the bottom attaching flange 15 of an upper combined valve and safety mechanism housing 16. This housing has a bottom wall or floor member 17 provided with a valve opening or port 18 for connecting the interior thereof with the interior of the float chamber 10, there being an intermediate relatively small chamber 19 interposed between opening 18 and chamber 10 serving as a valve chamber. The housing 16 likewise has horizontal web or partition members 20, 21 therein, these being apertured in vertical alignment with valve opening 18 at 22, 23, respectively. Aperture 22 serves as a guide for the vertical reciprocation of a valve stem 24 while aperture 23 acts as a secondary valve opening or port communicating with the atmosphere. Stem 24 has secured thereto ball valve members 25, 26 coating respectively with valve openings 18, 23, the valve members being disposed on opposite sides of said openings. An extension of valve stem 24 projects downwardly beneath the ball valve 25 for engagement with float arm 13, whereby the valve members 25, 26 are elevated or lowered in accordance with the movement of float 11 in the float chamber. This stem extension is guided beneath valve member 25 by a guide or spider 26 secured to flange 15 of the housing 16.

In normal operation when the valve members are elevated by lifting engagement of float arm 13 with the valve stem the passage of liquid through inlet valve opening 18 is cut off, the interior of housing 16 being then placed in communication with the atmosphere through port

23. The member 21 shown covering the upper ball valve member 26 is a shield or guard integral with the closure 271 for upper housing 16 for protecting the upper valve member 26; the side wall of this member is spaced from the housing at 272 for the entrance of air. To enable the ball valve members 25, 26 to be adjusted as desired relative to one another the valve stem is preferably threaded for the adjustable mounting of at least one of the valve members thereon.

An auxiliary safety float 28 is disposed in a compartment 29 of the housing 16 laterally adjacent and communicating with valve port 18. This float is vertically guided by a stem 30 thereon which is slidably in a guide 31 disposed internally of said compartment. The top of compartment 29 has an air passage 32 therein communicating with the air line 7, this passage entering the compartment through a valve opening or port 33 which is controlled by safety ball valve member 34. This valve member 34 is adjustably mounted on an extension 35 of stem 30 whereby the valve and float are suitably guided in the housing 16. A bleeder or vent cock 36 is tapped in said housing above and in communication with valve opening 33 and air passage 32, this cock being manually adjustable to admit air into the housing when desired so as to break any vacuum existent therein.

It will be noted that a small air bleeder opening or vent 37 is likewise formed in the partition of housing 16 in which the control valve opening 18 is disposed, this bleeder vent opening serving to prevent unequal pressure conditions on opposite sides of the partition.

In operation when the vent or bleeder cock 36 is closed, the vacuum of the intake manifold is effective to draw air from the pump casing 1 through the priming device. Attending the withdrawal of the air and as water is likewise drawn through the connection of the primer, it fills the lower chamber 10 raising the float and float controlled ball valve member 25 to shut off the flow of water further in the primer. If the float operates properly to terminate the liquid flow when chamber 10 is filled, the auxiliary safety trap mechanism in housing 16 does not come into operation. However, if the mechanism in the lower chamber 10 fails to operate as a result of jamming or other cause, control valve member 25 will not be seated against opening 18 and the liquid will rise into the upper chamber 29 lifting safety float 28 and closing the safety ball valve 34 so as to effectively cut off communication of the engine vacuum with the primer and prevent water from being drawn into the intake manifold. The area of the ball valve 34 exposed in the opening 33 is such that the float 28 and ball 34 are held against the seat or opening 33 even though the water level recedes slightly in the upper safety chamber 29. Obviously then, the primer cannot be operated again until the vent or bleeder cock 36 is opened permitting air to enter and release ball member 34 from its seat on opening 33.

If by chance the lower float mechanism has failed or jammed so that the operator cannot prime the pump and he finds that the safety mechanism 28-34 has operated, if he releases the same by venting air in the manner described and starts to prime over again, similar results will be obtained, which will indicate clearly to the operator that the primer is not functioning properly and needs investigation. Hence it follows that failure of the primer, if it occurs, is readily de-

tected without causing any destructive effect on the engine.

Though particularly devised for use in connection with a gasoline engine induced vacuum, it is evident that the improved priming device of the present invention is useful regardless of the particular source of vacuum.

Embodiments of the invention which incorporate the principles of the invention in a highly desirable manner have been illustrated and described. It should be understood that the foregoing terminology is used only descriptively rather than in a limiting sense, and with full intention to include equivalents of the features shown and described, within the scope of the following claims.

Having thus described our invention, what we claim as new and desire to secure by Letters Patent is:

20. 1. In a priming device of the class described, the combination of a main float chamber adapted to be connected to a pump to be primed, an auxiliary float chamber disposed in an elevated relation to said main float chamber and having a suction line port at the top thereof, a port connecting the top of said main float chamber with the bottom of said auxiliary float chamber, an upwardly seating main valve coacting with said port, a float in said main float chamber operatively associated with said main valve for closing the same when the main float is actuated, an air vent valve operatively connected to said main valve to be closed when said main valve is opened and to be opened when said main valve is closed

30 for admitting air to said suction line through said auxiliary float chamber, there being a restricted bleeder connection between said float chambers, an upwardly seating auxiliary safety valve coact-

40 ing with said suction line port, a float in said auxiliary float chamber operatively associated with said auxiliary safety valve to close the same when the float in said auxiliary float chamber is actuated, and a manually controlled suction line 45 vent valve disposed at the rear of said auxiliary safety valve, said auxiliary float chamber and said auxiliary float being of such relative dimensions that a surge of water in said auxiliary chamber tends to actuate the auxiliary float to 50 seat the auxiliary safety valve, the inlet to said auxiliary float chamber being below said auxiliary float.

2. In a priming device of the class described, the combination of a main float chamber adapted 55 to be connected to a pump to be primed, an auxiliary float chamber disposed in an elevated relation to said main float chamber and having a suction line port at the top thereof, a port connecting the top of said main float chamber with

60 the bottom of said auxiliary float chamber, an upwardly seating main valve coacting with said port, a float in said main float chamber operatively associated with said main valve for closing the same when the main float is actuated, an air vent valve operatively connected to said main valve to be closed when said main valve is opened and to be opened when said main valve is closed for admitting air to said suction line through said auxiliary float chamber, an upwardly seating auxiliary safety valve coacting with said suction line port, a float in said auxiliary float chamber operatively associated with said auxiliary safety

70 valve to close the same when the float in said auxiliary float chamber is actuated, and a manu-

ally controlled suction line vent valve disposed at the rear of said auxiliary safety valve.

3. In a priming device of the class described, the combination of a main float chamber adapted to be connected to a pump to be primed, an auxiliary float chamber disposed in an elevated relation to said main float chamber and having a suction line port at the top thereof, a port connecting the top of said main float chamber with the bottom of said auxiliary float chamber, an upwardly seating main valve coacting with said port, a float in said main float chamber operatively associated with said main valve for closing the same when the main float is actuated, an air vent valve operatively connected to said main valve to be closed when said main valve is opened and to be opened when said main valve is closed for admitting air to said suction line through said auxiliary float chamber, an upwardly seating auxiliary safety valve coacting with said suction line port and a float in said auxiliary float chamber operatively associated with said auxiliary safety valve to close the same when the float in said auxiliary float chamber is actuated.

4. In a priming device of the class described, the combination of a main float chamber adapted to be connected to a pump to be primed, an auxiliary float chamber connected to said main float chamber and having a suction line connection, a main valve for controlling said connection for said float chamber, a float in said main float chamber operatively associated with said main valve for closing the same when the main float is actuated, an air vent valve operatively connected to said main valve to be closed when said main valve is opened and to be opened when said main valve is closed for admitting air to said suction line, there being a restricted bleeder connection between said float chambers, an auxiliary safety valve for controlling said suction line connection of said auxiliary chamber, a float in said auxiliary chamber operatively associated with said auxiliary safety valve to close the same when the float in said auxiliary chamber is actuated, and a manually controlled suction line vent means dis-

posed at the rear of said auxiliary safety valve, said auxiliary chamber and said auxiliary float being of such relative dimensions that a surge of water in said auxiliary chamber tends to actuate 5 the auxiliary float to seat the auxiliary safety valve.

5. In a priming device of the class described, the combination of a main float chamber adapted to be connected to a pump to be primed, an auxiliary float chamber connected to said main float chamber and having a suction line connection, a main valve for controlling said connection for said float chamber, a float in said main float chamber operatively associated with said main 10 valve for closing the same when the main float is actuated, an air vent valve operatively connected to said main valve to be closed when said main valve is opened and to be opened when said main valve is closed for admitting air to said suction line, an auxiliary safety valve for controlling said suction line connection of said auxiliary chamber, a float in said auxiliary chamber operatively associated with said auxiliary safety valve to close the same when the float in said auxiliary chamber is actuated, and a manually controlled suction line vent means disposed at the rear of said auxiliary safety valve.

6. In a priming device of the class described, the combination of a main float chamber adapted to be connected to a pump to be primed, an auxiliary float chamber connected to said main float chamber and having a suction line connection, a main valve for controlling said connection for said float chamber, a float in said main float chamber operatively associated with said main valve for closing the same when the main float is actuated, an auxiliary safety valve for controlling said suction line connection of said auxiliary chamber and a float in said auxiliary chamber operatively associated with said auxiliary safety valve to close the same when the float in said auxiliary chamber is actuated.
